Primary Examiner—Susan J. Lucas

[57] CLAIM

The ornamental design for a suspended decorative lamp, as shown and described.

DESCRIPTION

FIG. 1 is a front view of a suspended decorative lamp showing my new design, the rear being a mirror image;

FIG. 2 is a bottom view thereof;

FIG. 3 is a side elevational view thereof, the opposite side being a mirror image; and,

FIG. 4 is a top view thereof.

The broken line showing of a bulb in FIGS. 1 and 3 is for illustrative purposes only and forms no part of the claimed design.
